UNITED STATES PATENT OFFICE.

ELMYR A. LAUGHLIN, OF OREGON, ILLINOIS, ASSIGNOR OF ONE-HALF TO Q & C COMPANY, OF NEW YORK, N. Y., A CORPORATION OF MAINE.

CAR BEARING.

Application filed November 26, 1921. Serial No. 517,854.

My invention relates to improvements in car bearings and more particularly to emergency side bearings for railway cars, the object of the invention being to provide a simple and efficient construction of this character, capable of economical manufacture.

Other objects will appear hereinafter.

The invention consists in the combinations and arrangements of parts hereinafter described and claimed.

The invention will be best understood by reference to the accompanying drawings forming a part of this specification, and in which,

Fig. 1 is a side view, shown partially in section, of a side bearing embodying the invention,

Fig. 2 is a top plan view thereof,

Fig. 3 is a section taken on line 3—3 of Fig. 1,

Fig. 4 is a top plan view of a modified form of construction,

Fig. 5 is a side view of the same shown partially in section, and

Fig. 6 is a section taken on line 6—6 of Fig. 5.

The form of construction illustrated in Figs. 1, 2, and 3 comprises a lower housing 7 adapted and arranged to be secured to the side frame 8 of a railway truck by means of rivets 9, one of said housings being secured to each side frame of the truck in the usual manner.

A roller 10 is arranged to operate within the housing 7, the top of said roller protruding slightly from the top of said housing as shown, in order to contact with the co-operating wear plate 11 secured to the corresponding end of the body bolster of the car. The housing 7 is provided in its bottom with a central wear plate 12 sloping upwardly each way from the center as shown, so as to exert a tendency on the roller 10 to return automatically to central position, and said wear plate having its upper bearing surface transversely and concavely curved. The bearing surfaces of the roller 10 are transversely and convexly curved, as shown, on a larger radius than the transverse curvature of the wear plate 12 and whereby said roller is caused to contact with the wear plate along two separated lines of contact 13 and to contact with the wear plate 11 along a central line of contact 14 as indicated in

Fig. 3. In rounding a curve the car body 55 pivots with reference to the truck so that the wear plate 11 travels in the arc of a circle with reference to the roller 10 and this movement exerts a lateral thrust on the roller 10 as it moves tending to crowd said roller 60 against the side walls of the housing. The curvature of the roller and the wear plate 12 effecting two parallel lines of contact, tends to keep the roller straight in its travel and prevent crowding thereof against the side 65 walls of the housing, a result which is materially augmented by the central line contact between the wear plate 11 and the roller, such line contact permitting of easy readjustment and lateral movement between the 70 wear plate 11 and the roller.

The roller 10 is provided at its sides with central trunnions 15 operating in longitudinal raceways 16 provided in the sides of the housing 7. The bottoms 17 of these raceways slope upwardly each way from the center at an inclination slightly greater than the inclination of the wear plate 12 and whereby said roller will be automatically lifted from contact with the wear plate 12 at each end 80 of its travel. The ends 17' of the bottoms of the raceways are upwardly curved or rounded to constitute bearings for the trunnions 15 and whereby, when the roller reaches the end of its travel, it is free to rotate on 85 the trunnions 15 to permit further movement of the wear plate 11 if necessary and reduce the friction of such movement.

Two ribs 18 are extended from each end of the wear plate 12 and are upwardly curved 90 as shown to fit the periphery of the roller 10 and whereby, upon failure of the trunnions 15 or after undue wear thereon, the roller 10 will rest upon the tracks 18 and turn thereon as a bearing so as to permit of 95 additional movement of the wear plate 11 if necessary.

The side walls of the housing 7 and the outer walls of the raceways 16 are upwardly tapering in form as shown, to provide clearance spaces 19 between the sides of the roller 10 and the ends of the trunnions 15 and whereby in case the roller is caused to crowd in either direction against the corresponding side of the housing or the outer wall of the raceway, such contact will take place at a point low on the side or outer walls, where said walls are thicker and stronger, and

where the bending moment tending to burst out said walls is the least. In this way a strong and durable construction is provided in which the housing for the roller may be 5 cast all in one piece. Channels 19' are formed along the sides of the wear plate 12, said channels permitting of the ready casting of the housing with comparatively close fitting of the roller and comparatively sharp 10 edges on the wear plate 12.

The modified form of construction illustrated in Figs. 4 to 6 inclusive, is the same as that already described except that the side trunnions are omitted from the roller 10', 15 and the corresponding raceways are omitted from the housing 7'. Otherwise the construction is identical with that already described. By means of this modified arrangement, a very economical bearing is provided which will operate satisfactorily under certain conditions especially where light, or lightly loaded cars are operated. The omission of the trunnions 15, of course omits their function but the roller 10' will 20 operate on the curved bearing surfaces of the tracks 18 and thus permit of additional motion of the wear plate 11 without undue friction, the tracks 18 relieving the friction of such operation to a certain extent.

While I have illustrated and described the preferred forms of constructions for carrying my invention into effect, these are capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. A car bearing comprising opposed bearing members, one being substantially flat and 45 the other transversely curved; and a rotatable bearing interposed between said bearing members and having its corresponding bearing surface transversely curved on a larger radius than said transversely curved bearing member, substantially as described.

2. A car bearing comprising upper and lower opposed bearing members, the upper bearing member being substantially flat and the lower transversely curved; and a rotatable bearing interposed between said bearing members and having its bearing surface transversely curved on a larger radius than said lower bearing member, substantially as described.

3. A car bearing comprising a lower housing 60 provided in its bottom with a central transversely curved wear plate; two tracks extending from each end of said wear plate, the ends of said tracks being upwardly curved; a roller arranged in said housing,

the bearing surface of said roller being transversely curved on a larger radius than said wear plate; central trunnions on the sides of said roller, there being longitudinal raceways in the sides of said housing to receive said trunnions, the bottoms of said raceways sloping upwardly each way from the center to lift said roller from contact with said wear plate at the end of the travel thereof; and a substantially flat wear plate 70 resting upon the top of said roller and making substantially central line contact therewith, substantially as described.

4. A car bearing comprising a lower housing 80 provided with upwardly tapering side walls and in its bottom with a central transversely curved wear plate; two tracks extending from each end of said wear plate, the ends of said tracks being upwardly curved; a roller arranged in said housing, the bearing surface of said roller being transversely curved on a larger radius than said wear plate; central trunnions on the sides of said roller, there being longitudinal raceways in the sides of said housing to receive said trunnions, the bottoms of said raceways sloping upwardly each way from the center to lift said roller from contact 85 with said wear plate at the end of the travel thereof; and a substantially flat wear plate 90 resting upon the top of said roller and making substantially central line contact therewith, substantially as described.

5. A car bearing comprising a housing 100 having a central wear plate; and roller supporting tracks at each end of said wear plate and constituting continuations thereof, substantially as described.

6. A car bearing comprising a housing 105 having a central wear plate; and roller supporting tracks at each end of said wear plate and constituting continuations thereof of curved at their ends to fit the peripheries of a roller, substantially as described.

7. A car bearing comprising a housing 110 having a central wear plate; roller supporting tracks at each end of said wear plate and constituting continuations thereof; a roller in said housing; central trunnions on the sides of said roller; there being longitudinal raceways in the sides of said housing to receive said trunnions, the bottoms of said raceways sloping upwardly each way from the center to lift said roller from contact with said wear plate at the 115 end of its travel; and a co-operating wear plate making contact with said roller, a portion of said roller protruding from said housing for this purpose, substantially as described.

8. A car bearing comprising a housing 120 having a central wear plate; roller supporting tracks at each end of said wear plate and constituting continuations thereof, the ends of said tracks being upwardly curved;

- a roller in said housing; trunnions on the sides of said roller, there being longitudinal raceways in the sides of said housing to receive said trunnions, the bottoms of said raceways sloping upwardly each way from the center to lift said roller from contact with said wear plate at the ends of its travel, the ends of the bottoms of said raceways being upwardly curved to constitute bearings for said trunnions; and a co-operating wear plate making contact with said roller, a portion of said roller protruding from said housing for this purpose, substantially as described.
- 15 9. A car bearing comprising a lower housing having upwardly tapering side walls and a central transversely curved wear plate in its bottom; two roller supporting tracks leading from each end of said wear plate, the ends of said tracks being upwardly curved to form roller bearings; a roller arranged in said housing and having transversely curved bearing surfaces curved on a larger radius than said wear plate; central trunnions on the sides of said roller, there

being longitudinal raceways provided in the sides of said housing to receive said trunnions, the bottoms of said raceways sloping upwardly each way from the center to raise said roller from contact with said wear plate at the ends of its travel, the ends of the bottoms of said raceways being curved to constitute bearings for said trunnions; and a substantially flat wear plate contacting with the top of said roller, substantially as described.

10. A car bearing comprising upper and lower opposed bearing members, the upper bearing member being flat and the lower bearing member being transversely and concavely curved; and a rotatable bearing interposed between said bearing members, said rotatable bearing being transversely and convexly curved but having less curvature than said lower bearing member, substantially as described.

In testimony whereof I have signed my name to this specification.

ELMYR A. LAUGHLIN.
